ELECTRICAL SIGNAL DEVICE AND SYSTEM

Edmund M. Squire, Brooklyn, N. Y., and Owen W. Kennedy, Boylston, Mass., assignors to Signal Engineering & Manufacturing Company, New York, N. Y., a corporation of Massachusetts

Application June 20, 1935, Serial No. 27,576

6 Claims. (Cl. 179—84)

The present invention relates to electrically operated signals, and has for its object to provide an improved signal device and a system particularly adapted for use in connection with existing telephone installations for the purpose of signaling incoming calls in a manner different from that of the telephone bells usually employed.

In the copending application of John H. Wheelock, Serial No. 697,417 filed November 10, 1933, there is shown and described an auxiliary signaling device of the above indicated character, with each signal obtaining its operating current from a source independent of the telephone installation, such as any light or power circuit, 15 while receiving its primary energization from telephone ringing current. Furthermore, each auxiliary signal unit is so connected to the bell of the existing telephone installation that while the auxiliary signal will ordinarily be operated in place of the telephone bell, the latter will be automatically rendered operative upon any failure of the source from which the auxiliary signal is energized, or upon disconnection of the unit from this source.

While an auxiliary signal such as is described in the aforementioned Wheelock application is entirely satisfactory for the general purpose of signaling an incoming telephone call in place of the usual bell, no provision is made for causing the telephone bell to ring in the event of the occurrence of conditions which would render the auxiliary signal inoperative. Accordingly, the present invention provides means whereby an auxiliary signal of the type disclosed in the Wheelock application is continuously supervised, so that the telephone bell is automatically placed in condition for ringing in response to an incoming call upon the occurrence of any abnormal condition which would prevent the auxiliary signal from functioning. The above and other advantageous features of the invention are herein-after more fully set forth in the following description with reference to the accompanying drawing, in which:—

Fig. 1 is a general wiring diagram illustrating the manner of installing auxiliary signals embodying the invention in connection with telephone subscriber's stations.

Fig. 2 is a view showing, on an enlarged scale, 50 the construction of one of the auxiliary signal units.

Fig. 3 is a view similar to Fig. 2, illustrating a modification of the invention.

Like reference characters refer to like parts in the different figures.

Referring first to Fig. 1, there is illustrated diagrammatically, a number of subscriber's stations S, each providing the usual telephone instrument as indicated, and a subscriber's equipment box B, including a bell, all of usual construction. The complete wiring of the telephone set of a subscriber's station S is simplified to the extent of showing only conductors b leading to each box B from the central exchange C, with ringing means indicated at K associated with 10 the conductors b, see Fig. 2. As is usual, the conductors b are adapted to be energized at the central station C, so that telephone ringing current is transmitted to any box of a subscriber's station S upon operation of the ringing means K at 15 the central station.

Associated with each subscriber's station S is a portable signal unit I, preferably of the single stroke chime type described in the aforementioned Wheelock application. Each signal unit I provides a cable 2 carrying at its end a suitable plug 3 for insertion in a power outlet 4 located adjacent to the subscriber's station S. Each outlet 4 is energized from the mains 5 of a wiring installation, such as is usually provided for furnishing light and power to the building in which the subscriber's telephone set S is located. A signal unit I also provides a flexible conductor cord 6 having a number of tips 7 for convenient connection to a terminal block 8 on the subscriber's instrument box B, so that to install a signal unit it is only necessary to mount the unit adjacent to the nearest box B and power outlet 4, followed by insertion of the plug 3 in an outlet 4 and connection of the cord 6 to the box 25 terminal block 8.

Referring now to Fig. 2, each signal unit I consists of a resonant chime member 9 disposed in the path of movement of a magnetic plunger 10 movable axially within an operating winding 11. 40 With the winding 11 in a deenergized condition, only the upper end of the plunger 10 is disposed within the solenoid, so that energization of the winding 11 is adapted to draw the plunger upwardly to strike the resonant member 9 a single sharp blow. One terminal of the winding 11 is connected directly to one of the conductors 2a of the cable 2, while the other winding terminal 11 is connected in series with a winding 12 of a supervisory relay through a condenser 13. The current flowing through the winding 11 in series with the winding 12 is not sufficient to pull up the plunger 10, although sufficient current traverses winding 12 to maintain the bridging member 14 carried by its armature 12a in engagement 45 50 55

with spaced stationary contacts 15 and 16. The contact 15 is connected to one terminal of an auxiliary winding 17 forming part of the signal unit, with the other terminal of winding 17 connected through a condenser 18 to one conductor 6a of the cord 6 leading to the box B. The other contact 16 of the supervisory relay is connected to a second conductor 6b leading to the box B, so that when the space between the contacts 15 and 16 is closed by the bridging member 14, the terminals of the auxiliary winding 17 are connected across the line terminals L-1 and L-2 of the box B in circuit with the condenser 18.

The armature 17a under the control of winding 17 carries separate contact arms 19 and 20 insulated from each other, which arms are adapted to engage stationary contacts 21 and 22 respectively, upon energization of the winding 17. The arm 19 is connected to the conductor 2b of the power cable 2, while its cooperating contact 21 is connected to the signal winding 11 in parallel with one side of the condenser 13. The other contact arm 20 is connected to the power conductor 2a, while its cooperating contact 22 is connected in parallel with the supervisory winding 12 and the opposite side of the condenser 13.

The equipment in the box B is of any usual type, and is shown as providing bell ringing coils 23, which upon energization by ringing current 30 will cause the subscriber's bell to ring. One terminal of the ringer coils 23 is connected to box line terminal L-2, which in turn is connected to one conductor b leading from the ringing means K, while the other ringer coil terminal is connected to the third conductor 6c of the cord 6. This conductor 6c is connected to one of a pair of spaced stationary contacts 24, the other of which is connected to the conductor 6b in parallel with the contact 16. The gap between the spaced contacts 24 is adapted to be closed by the bridging member 14 only upon deenergization of the supervisory winding 12. Consequently, the conductor 6b, which is connected permanently through box line terminal L-1 to the other conductor b from the ringing means K is adapted to transmit ringing current either to the auxiliary signal winding 17 or to the ringer coils 23, entirely depending upon the position of the bridging member 14 with reference to the cooperating pairs of spaced contacts 15, 16 and 24, 24.

With the plug 3 of the signal unit 1 inserted in a power outlet 4, it is obvious that the terminal of the ringer coils 23 connected to the contact 24 by conductor 6c will be maintained disconnected from the return conductor 6b so long as supervisory current flowing through the winding 12 maintains the bridging member 14 out of engagement with the spaced contacts 24. Therefore, when the ringing means K is operated to supply ringing current to this particular subscriber's station S, the bell will not be rung, but the ringing current will energize the auxiliary signal winding 17 to cause its contact arms 19 and 20 to engage stationary contacts 21 and 22.

Energization of the auxiliary winding 17 has the effect of changing the series connection of the windings 11 and 12 across the supply mains to a parallel circuit relation, due to the fact that closure of contacts 19 and 21 connects one terminal of winding 11 to the conductor 2b, while closure of contacts 20 and 22 connects the corresponding terminal of winding 12 to conductor 2a. Upon connection of the winding 11 directly across the supply mains, its full energization draws the plunger 10 upwardly to strike the reso-

nant member 9 a single sharp blow, the plunger remaining in this position as long as ringing current is applied. The sound emitted by the resonant member 9 is of a clear penetrating quality, and a single stroke thereon is sufficient to call 5 the subscriber's attention to the fact that there is an incoming call. In case the subscriber does not answer immediately, subsequent re-applications of ringing current, as is the usual practice, results in reenergizations of the winding 11 to 10 again sound the chime one or more strokes. Obviously, recurrent strokes of the chime will be much less disturbing to the ear than the continued ringing of the bell in box B during the full period of application of ringing current from the 15 central station C. The connection of the supervisory winding 12 directly across the supply mains, upon closure of contacts 20 and 22, insures the continued energization of this winding, so that the bell is maintained inoperative as before. 20

Upon failure of the source supplying the conductors 2a and 2b, upon disconnection of the signal unit from the outlet 4, or upon a break in the circuit of the signal operating winding 11, the deenergization of winding 12 will result in two 25 things:—first, dropping back of the bridging member 14 to engage the spaced contacts 24 will establish the circuit of the ringer coils 23 from the conductor 6c to the conductor 6b,—second, disengagement of the bridging member 14 from 30 the contacts 15 and 16 will entirely disconnect the auxiliary winding 17 from the conductor 6b. Therefore, when ringing current is applied with the winding 12 deenergized, as a result of any one of the three occurrences mentioned above, 35 only the ringer coils 23 will be energized to sound the bell at the subscriber's station. In other words, upon the occurrence of any abnormal condition which renders the auxiliary signal inoperative, the bell will be rung in response to an incoming call, thereby insuring continuity of telephone service. On the other hand, so long as the supervisory winding 12 remains energized, the chime signal will be sounded in response to each 40 application of ringing current. While the supply 45 mains 5 are indicated as being energized from an alternating current source, the auxiliary signal will operate just as effectively when utilizing a direct current source by substituting a resistor 25 for the condenser 13 in the circuit between the 50 windings 11 and 12, as indicated in dotted lines in Fig. 2.

Referring now to Fig. 3, there is shown a modification of the manner of supervising the winding 11', wherein a resistor 26 is connected between 55 one terminal of the winding 11' and the conductor 2b. With the resistor 26 in circuit with the winding 11', its current is reduced to such an extent that the plunger 10' is held slightly above its lowermost position, as indicated in full lines. 60 However, should there occur a break in the winding 11', the plunger 10' will drop to its lowermost position indicated in dotted lines.

The same terminal of the winding 11' which is connected to the resistor 26 is also connected to 65 one of a pair of spaced stationary contacts 27, the other contact of this pair being connected to power conductor 2b. The contacts 27 are adapted to be connected by a bridging member 28 under the control of a winding 17', one terminal of which is connected through condenser 18' to the conductor 6a leading from the line terminal L-2 of the subscriber's station. The other terminal of winding 17' is connected to a stationary contact 29 normally in engagement with a 75

flexible contact 30 connected to conductor 6b leading from box terminal L-1.

With the plunger 10 held in its slightly raised position by the supervisory current traversing winding 11', an insulated tip 30a of the contact 30 is just out of engagement with the lower end of plunger 10'. Consequently, an application of ringing current to the subscriber's station will cause energization of winding 17', and the closure of the gap between contacts 27 to short circuit the resistor 26 and fully energize the signal winding 11'. In other words, the main signal winding 11' will function in exactly the same manner as the winding 11 of Fig. 2, as long as it is traversed by the supervisory current.

Upon the occurrence of a break in the circuit of the winding 11', the plunger 10' will fall to its lowermost position, thereby moving contact 30 out of engagement with contact 29 and causing it to engage a lower contact 31. Since contact 31 is connected to conductor 6c leading to the bell coils 23, the telephone bell will be sounded upon each application of ringing current so long as the plunger 10' remains in its lowermost position, as a result of the absence of supervisory current flowing in the winding 11'.

From the foregoing, it is apparent that by the present invention there is provided an improved signal unit that is particularly adapted for use in connection with existing telephone installations for the purpose of indicating incoming calls at any subscriber's station in a more pleasing and effective manner than that afforded by the usual telephone bell. At the same time, the occurrence of any abnormal condition which renders the auxiliary signal inoperative immediately results in the indication of an incoming call being restored to the telephone ringer.

We claim:

1. In an electrical signal system, the combination with separate current sources, a signal device comprising a winding which causes operation of said signal when fully energized from one current source, a second winding responsive to the other current source for controlling the connection of the signal operating winding to the first source, a second signal device and means responsive to the flow of supervisory current of low value through said signal operating winding from said first-named source for maintaining a circuit to said second winding and for also maintaining the second signal device inoperative from said other current source.

2. In an electrical signal system, the combination with separate current sources, a signal device comprising a winding which causes operation of said signal when fully energized from one current source, a second winding responsive to the other current source for controlling the connection of the signal operating winding to the first source, a second signal device and means responsive to the flow of supervisory current of low value through said signal operating winding

from said first-named source for maintaining a circuit to said second winding and for also maintaining the second signal device inoperative from said other current source, with the occurrence of any interruption of the flow of supervisory current through said operating winding of the first signal device serving to automatically restore the second-named signal device to an operative condition.

3. In a telephone system, the combination with 10 a source of ringing current, a telephone ringer at a subscriber's station and a source of commercial power, of an auxiliary signal device comprising a winding which causes operation of said signal when fully energized from said power source, a second winding responsive to a ringing current for controlling the connection of said signal operating winding to said power source, and means responsive to the flow of supervisory current of low value through said signal operating winding from said power source for maintaining a circuit to said second winding and for maintaining said ringer inoperative by ringing current.

4. In a telephone system, the combination with 25 a source of ringing current, a telephone ringer at a subscriber's station and a source of commercial power, of an auxiliary signal device comprising a winding which causes operation of said signal when fully energized from said power source, a second winding responsive to a ringing current for controlling the connection of said signal operating winding to said power source, and means responsive to the flow of supervisory current of low value through said signal operating winding from said power source for maintaining a circuit to said second winding and for maintaining said ringer inoperative by ringing current.

5. A signal unit of the class described, comprising an operating winding responsive to one current source, a second winding responsive to another current source for controlling the connection of the operating winding to the first source, and means responsive to the flow of supervisory current through said operating winding from said first-named source for maintaining a 50 circuit to said second winding.

6. A signal unit of the class described, comprising an operating winding responsive to one current source, a second winding responsive to another current source for controlling the connection of the operating winding to the first source, and a third winding normally in series with the operating winding for maintaining a circuit to said second winding, as long as supervisory current flows through the first and third 60 windings.
